UNITED STATES PATENT OFFICE.

SAMUEL KLEINMAN, OF LOS ANGELES, CALIFORNIA.

DESIGN FOR A PIN, BROOCH, BRACELET, FINGER RING, OR ARTICLE OF SIMILAR NATURE.

60,991.

Specification for Design. Patented May 23, 1922.

Application filed June 15, 1921. Serial No. 477,836. Term of patent 3½ years.

To all whom it may concern:

Be it known that I, SAMUEL KLEINMAN, a citizen of the United States, residing at Los Angeles, in the county of Los Angeles and State of California, have invented a new, original, and ornamental Design for a Pin, Brooch, Bracelet, Finger Ring, or Article of Similar Nature, of which the following is a specification, reference being had to the accompanying drawing, in which—

Figure 1 is a plan view of the design.

Figure 2 is a view in cross section seen on the line 2—2 of Figure 1.

Figure 3 is view in section as seen on the line 3—3 of Figure 1.

Fig. 4 is a perspective view, illustrating the design as applied to a finger-ring.

The design consists of a series of heart-shaped elements spaced apart with a spray of leaf-like elements interposed therebetween.

The design is applicable to various articles of jewelry, namely, pins, brooches, bracelets, finger rings, and articles of similar nature, being particularly applied to wedding rings and the like.

I claim:—

The ornamental design for a pin, brooch, bracelet, finger ring, or article of similar nature, substantially as shown and described.

SAMUEL KLEINMAN.
